UNITED STATES PATENT OFFICE.

THEODORE HAVILAND, OF AMBAZAC, FRANCE.

DESIGN FOR A DISH.

SPECIFICATION forming part of Design No. 22,979, dated December 19, 1893.

Application filed October 27, 1893. Serial No. 489,317. Term of patent 7 years.

To all whom it may concern:

Be it known that I, THEODORE HAVILAND, a citizen of the United States, residing at Ambazac, in the Department of Haute-Vienne and Republic of France, have invented and produced a new and original Design for Dishes; and I do hereby declare the following to be a full, clear, and exact description of the same, reference being had to the accompanying drawings, forming a part thereof.

Figure 1 represents a side view of a covered dish. Fig. 2 represents a face view of the cover of said dish.

The principal feature of my design consists in having the upper outer edge of the dish marked with four regular series of gaufferings that have a leaf-like ornamentation covering their base. The configuration extends to nearly the middle of the dish where it is terminated by an undulating line.

In Fig. 1 A A represent the series of gaufferings which seem to rise from the leaf-like ornamentations B B. A slightly undulating line C divides the ornamentations from the lower portion of the dish. The foot of the dish is marked by a gauffered edge D which passes around the periphery of the dish.

In Fig. 2 the series of gaufferings is shown by the letters a a.

What I claim is—

The design for dishes substantially as shown and described.

In testimony whereof I affix my signature in presence of two witnesses.

THEODORE HAVILAND.
